(57) **CLAIM**

The ornamental design for a food cutter, as shown and described.

DESCRIPTION

1. Food cutter

1.1 is a top front perspective view of a food cutter showing my new design;

1.2 is a left side view thereof;

1.3 is a right side view thereof;

1.4 is a top view thereof;

1.5 is a bottom view thereof;

1.6 is a front elevation view thereof;

1.7 is a rear elevation view thereof;

1.8 is a top perspective view thereof in a closed state; and

1.9 is a bottom perspective view thereof in a closed state. Reproductions 1.1-1.7 show the food cutter in an open state; reproductions 1.8-1.9 show the food cutter in a closed state.
